UNITED STATES PATENT OFFICE.

LEONELL R. HAGE, OF FAIRFIELD, MONTANA.

DOOR-STOP.

1,374,731.

Specification of Letters Patent. Patented Apr. 12, 1921.

Application filed May 1, 1920. Serial No. 378,103.

To all whom it may concern:

Be it known that I, LEONELL R. HAGE, a citizen of the United States, residing at Fairfield, in the county of Teton, State of 5 Montana, have invented certain new and useful Improvements in Door-Stops; and I do hereby declare the following to be a full, clear, and exact description of the invention, such as will enable others skilled in the art 10 to which it appertains to make and use the same.

This invention relates to builders' hardware, and more especially to door checks; and the object of the same is to produce a 15 buffer or cushion for checking or stopping the movement of a door to its closed position, so as to prevent the noise produced in slamming.

The invention is carried out preferably 20 by attachments to or elaborations in the face plate of the lock and the strike or keeper plate of the frame, and in either case provision is made for adjustments to adapt the device to doors of different thicknesses, and 25 perhaps later to set the device so that it will work successfully although the door or frame or both may change their position a little in time.

Details of construction are set forth below 30 and shown in the drawings wherein:

Figure 1 shows the front plate of a lock which is manufactured with this attachment on it, Fig. 2 a strike plate so manufactured, and Fig. 3 is a section on the line 3-3 of 35 Fig. 2.

Fig. 4 shows the attachment applied to the front plate of an old lock, Fig. 5 shows the strike plate and its attachment which must be substituted when the structure in 40 Fig. 4 is applied, and Fig. 6 is a vertical section through the strike on the line 6-6 of Fig. 5.

Fig. 7 is a detail to be referred to herein-after, and Fig. 8 is a partial view of the 45 blank from which the lock attachment in Fig. 4 is made.

In the drawings I have used the letter F to designate the front plate of an ordinary door lock whereof L is the latch and B is 50 the bolt, and the letter S designates the keeper plate or strike which is attached to the door frame and has openings O for said latch and bolt, both plates having holes H for the usual attaching screws. No novelty 55 is claimed for these elements in their ordinary function. As the door closes and

comes to rest against the bead on the frame, the plate F moves close across the face of the strike S and the tip of the latch L engages the upper opening O while the bolt B 60 when it is projected enters the lower opening. By a slight addition to these plates at the time they are made, my improvement can be applied to new locks as seen in Figs. 1 to 3, whereas the remaining views provide 65 for its attachment to doors already in use.

Referring first to Figs. 1 to 3, a metal plate or strip 1 projects from the rear edge of the front plate F, preferably opposite the latch L, and is herein shown as turned 70 over at its outer end into a lip 2 under which is carried a bumper such as a rubber block or plug 3. The front edge of the plate S will be found to be already provided with a little lip against which the beveled end of the 75 latch L strikes in closing the door, but in the present invention I elongate this lip into a strip 4 whose outer end is bent at an angle 5 and then carried to the rear in a flange 6 pierced with a threaded hole 7, and the bolt 80 opening O may be extended laterally to the angle but is preferably formed at its upper and lower edges with tongues 8.

The numeral 11 designates a plate or strip 85 having grooves 18 in its upper and lower edges slidably engaging said tongues, and its outer end is bent to the rear in a flange 16 having a slot 17. The numeral 18 designates a screw whose threads are engaged with the hole 7, this screw having a groove 90 19 just under its head which is engaged with said slot; and thereby the screw is swiveled in the flange 16 and threaded in the flange 6, and when it is turned in one direction or the other the strip 11 is adjusted over the 95 strip 4. In addition, the adjustable strip may have a series of openings or preferably a slot 12, and a set screw 13 may engage the fixed strip 4 and have its head standing within this slot, so that after adjustment 100 this screw can be set up tight to hold the parts.

In the closing of a door equipped with this invention, the latch L strikes first the angle 15 of the adjustable strip, and its tip 105 moves across this strip and drops into the opening O at its inner end, and just as the door reaches its closed position the bumper 3 strikes the outer face of the flange 16 so as to check the closing of the door before 110 the latter can strike the bead on the frame. If the parts should warp or otherwise be-

come changed by time and use, the set screw 13 can be loosened and the other screw turned to adjust the position of the strip slightly as is necessary, or of course a new 5 bumper or plug 3 could be inserted under the lip 2.

For application of this invention to doors already hung, reference is made to Figs. 4 to 8. The front plate F of the lock is here of 10 the usual type, and in order to provide it with the attachment which otherwise would have been applied at the time it was made, my invention contemplates a plate or strip 21 whose outer end can be turned over into 15 a lip 22 to carry a bumper or plug 23, whereas its inner end will originally be formed about as seen in Fig. 8. That is to say, this end is bifurcated and each arm of the bifurcation includes a long element or 20 tongue 24 and a short element or lip 25, the long element being intended to reach across the plate F and engage its far edge, whereas the short element is intended to engage its near or rear edge. In applying this plate 25 21 to the lock plate F as seen in Fig. 4, the tongue is bent back as at 26 and the lip is bent back and then forward as seen at 27, thus forming hooks which closely engage the edges of the plate F and will be passed into 30 recesses cut in the edge of the door behind said plate to admit them.

Thus one part of the attachment can be applied to the lock which is already on the door, but to alter the other so as to coact 35 with the modified lock, I prefer to replace the strike with that best seen in Fig. 5. This is in effect a duplicate of the strike shown in Figs. 2 and 3 and already described, excepting that the body of the plate 40 at that point where it has the latch opening is here deflected to the rear as shown at 9 in Fig. 6, and of course the frame must be appropriately cut out to admit a strike thus made. The purpose is obviously to permit 45 insetting the adjustable strip 11 beyond the face of the strike a sufficient distance to allow the plate 21 on the door to pass when the door is closed, because said plate 21 now overlaps the front plate F a distance 50 equal to its own thickness. Otherwise the construction and operation of the device is the same.

I have shown the flange 6 as provided with a hole 7 engaged by the screw, and the latter 55 as swiveled in the slot 17 in the flange 16, but of course this could be reversed or other adjusting means might be adopted. However, I consider it wise to have one of said openings a slot in order that the parts may 60 be readily assembled. Other means than the set screw 13 and slot 12 might be provided for locking the plate after its adjustment, or the adjustment itself might be provided with locking means. I have shown and 65 described this attachment as applied directly

opposite the latch L, and so prefer to locate it because the angle 15 of the adjustable strip will then take the place of the lip usually formed on the strike and engaged by the latch as the door closes; but it will 70 be clear that the attachment is not limited in its application to this exact position. These and other details are subject to change as experience may indicate, and I reserve the broadest latitude in this respect. 75

What is claimed as new is:

1. In a door stop, the combination with a plate projecting from the free edge of the door, and a bumper in the projecting end of the plate; of a strip having at one end a 80 flange standing in the path of the bumper as the door closes, and means for adjustably connecting this strip with the door frame.

2. In a door stop, the combination with a plate projecting from the free edge of the 85 door, and a bumper in the projecting end of the plate; of a strip having at one end a flange standing in the path of the bumper as the door closes, the strike carried by the door frame, and means for adjustably connecting 90 said strip with the strike.

3. In a door stop, the combination with a plate projecting from the free edge of the door, and a bumper carried by said plate; of a strip having at one end a flange standing in the path of the bumper as the door closes, the strike carried by the door frame and having a laterally projecting strip underlying that last-named, and a threaded 95 element connecting the strips and permitting 100 their relative adjustment.

4. In a door stop, the combination with a bumper, and means for supporting it at the free edge of the door; of the lock strike carried by the door frame and having a 105 strip projecting from its edge and flanged, an adjustable strip overlying that named and also flanged, and a screw swiveled in one flange and threaded through the other. 110

5. In a door stop, the combination with a bumper, and means for supporting it at the free edge of the door; of the lock strike carried by the door frame and having a strip 115 projecting from its edge and flanged, an adjustable strip overlying that named and also flanged, a screw swiveled in one flange and threaded through the other, one strip being longitudinally slotted, and a set screw fast through said slot and engaging the other strip. 120

6. In a door stop, the combination with a bumper, and means for supporting it at the free edge of the door; of the lock strike adapted for attachment to the door frame and provided with a strip projecting from one edge, the strike having an opening with tongues along its horizontal edges, a strip having grooves in its edges slidably engaging said tongues and a flange to be struck by the bumper as the door closes, and means for 125 130

holding the strip in adjusted position within said opening.

7. The herein described door stop, the same comprising a plate carrying a bumper 5 at one end and having its other end slotted to form tongues and lips for engagement with the front plate of a door lock; a strike whose body is depressed on a transverse path opposite said plate on the door, a strip 10 whose outer end is adapted to be struck by the bumper as the door closes, and means for adjustably securing the strip in said depressed path.

8. The herein described door stop, the 15 same comprising a plate having means for

attaching it across a door lock opposite the latch thereof, and a bumper carried by the plate; a strike plate depressed on a transverse path across its latch opening, and a strip mounted in said path and projecting 20 beyond the edge of the strike and adapted to be struck by said bumper as the door closes.

In testimony whereof, I affix my signature, in the presence of two witnesses.
